LIGHT METAL CYLINDER HEAD FOR INTERNAL COMBUSTION ENGINES

Richard Kloss, Köln-Buchforst, Germany, assignor to Klöckner - Humboldt Deutz Aktiengesellschaft, Köln, Germany

Application November 28, 1955, Serial No. 549,465

Claims priority, application Germany December 6, 1954

5 Claims. (Cl. 123—193)

The present invention relates to a cylinder head of light metal for internal combustion engines, especially diesel engines. More specifically, the present invention relates to a cylinder head of the above type which at its sealing surface is provided with a compression ledge directly resting against the sealing surface of the cylinder and tightly connected to the latter by means of bolts evenly distributed over the circumference of the cylinder head.

Compression ledges for sealing purposes are known. However, in their heretofore known form these compression ledges cannot be used as sealing means proper between the cylinder head and the cylinder. With the heretofore known designs, the compression ledge is maintained as supporting element over its entire length even after the connecting bolts have been tightened. This arrangement has the drawback that the connection between cylinder and cylinder head is somewhat loosened following an operation of the cylinder. The reason for this consists in that during the operation of the cylinder heat stresses occur which bring about a further deformation of the compression ledge. When after completion of the operation of the cylinder the parts again cool down, there will exist a play between the cylinder head and the cylinder so that a leakage exists.

It is, therefore, an object of the present invention to provide a cylinder-cylinder head connection which will overcome the above mentioned drawbacks without requiring separate sealing means between the cylinder and the cylinder head.

It is another object of this invention to provide a cylinder head with a compression ledge for connection with a cylinder, in which the compression ledge will serve as highly satisfactory sealing means without requiring any additional gasket or the like.

These and other objects and advantages of the invention will appear more clearly from the following specification in connection with the accompanying drawings, in which:

Fig. 1 represents a vertical longitudinal section through a lower portion of a cylinder head according to the invention and the upper portion of a cylinder of an air cooled diesel engine.

Fig. 2 is a view along the line II—II of Fig. 1.

Fig. 3 shows a cylinder head according to the invention connected to the cylinder after the connecting bolts have been properly tightened.

Fig. 4 is a modification over the arrangement shown in Fig. 1.

General arrangement

The cylinder head according to the present invention provided with a compression ledge for engagement with the sealing surface of the cylinder is characterized in that the compression ledge is so dimensioned that within the range of the connecting bolts the compression ledge is completely flattened by the tightening force of the bolts so that the entire sealing surface of the cylinder head within the range of said bolts bears against the sealing surface of the

2

cylinder. In other words, when the connecting bolts are tightened the cylinder head so to speak fully sets on the sealing surface of the cylinder. Within the range of the connecting bolts the bearing surface of the now flattened compression ledge is so great that a deformation during the heating of the cylinder and cylinder head will be excluded. In the central portion between two connecting bolts, the deformation of the compression ledge is smallest. This is due to the fact that the cylinder head is not a completely bend-resistant unit. The bending of the cylinder head in the central portion between two connecting bolts is the reason why the deformation of the compression ledge outside the range of the connecting bolts becomes less with increasing distance from said bolts. The deformation is such that between the compression ledge and the sealing surface of the cylinder all the way around a substantially even specific pressure load occurs which remains also after the cylinder and cylinder head heat up.

In order to prevent a clamping along the collar of the cylinder due to the compression ledge giving way toward the sides, according to a further development of the invention the compression ledge is so arranged on the sealing surface of the cylinder head that within the range of the connecting bolts there will still remain a sealing surface of the cylinder at both sides of the compression ledge.

Instead of providing one annular compression ledge, also a plurality of smaller annular compression ledges may be provided in spaced relationship with regard to each other.

Structural arrangement

Referring now to the drawing in detail and Figs. 1 to 3 thereof in particular, the arrangement shown therein comprises a cylinder head 1 and a cylinder 2. While the cylinder 2 is made of cast iron or steel, the cylinder head 1 is made of light metal. The cylinder head 1 rests directly against the cylinder 2 without any gasket or other separate sealing means therebetween. The cylinder head 1 is connected to the cylinder 2 in a manner known per se by connecting bolts 3 extending through bores 3a in the cylinder head. The cylinder head 1 is provided with a compression ledge 4 by means of which it rests against the sealing surface 5 of the cylinder 2. The compression ledge is so dimensioned that when the bolts 3 are tightened, the compression ledge will completely flatten within the range of the bolts 3 so that the entire sealing surface 9 of the cylinder head will bear. According to tests, a compression ledge having a height of .2 millimeter has proved highly satisfactory with cylinders having an inner diameter of approximately 110 millimeters and an ignition pressure of from 80 to 90 atmospheres above atmospheric pressure. The connecting bolt tension should amount to about 1.5 to 3 times the ignition pressure multiplied by the piston surface and divided by the number of the connecting bolts. Assuming for instance a bolt tension of 2½ times the ignition pressure of 85 atmospheres above atmospheric pressure, a connecting bolt force of about 5250 kilograms will be obtained. The compression ledge according to the invention is so to be dimensioned that for instance at the said connection bolt pressure the compression ledge will completely flatten within the range of the connecting bolts so that within the range of said bolts the entire sealing surface of the cylinder will bear. With a connecting bolt force of 5250 kilograms and a height of about 0.2 millimeter of the compression ledge, the width of the latter is about 5 millimeters.

In Fig. 2, the solid lines 6 indicate the width of the compression ledge prior to the first installation of the cylinder head without any load exerted by the connecting bolts 3. However, when the bolts 3 are tightened, the compression ledge will deform along the dot dash line 7 of

Fig. 2. The course of the dot dash line 7 shows that the compression ledge 4 is within the range of the connecting bolts deformed more than in the central portion between two adjacent bolts 3. Within the range of the connecting bolts, the compression ledge is deformed to such an extent, as mentioned above that the entire sealing surface 9 of the cylinder head will bear within the range of the connecting bolts 3.

In order to prevent the cylinder head 1 from clamping itself against the collar 8 of the cylinder due to the lateral give-way of the compression ledge 4, the compression ledge 4 is arranged over a portion only of the width of the sealing surface 9 of the cylinder head 1. The compression ledge 4 is so distributed over the sealing surface 9 that a portion of the sealing surface 9 will remain at both sides of the compression ledge.

The embodiment shown in Fig. 4 differs from that of Figs. 1 and 2 in that the compression ledge 4 of Fig. 1 has been replaced by two smaller compression ledges 10, 10'.

It is, of course, understood that the present invention is, by no means, limited to the particular construction shown in the drawings but also comprises any modifications within the scope of the appended claims.

What I claim is:

1. A cylinder head of light metal for connection by connecting bolts with cast iron and steel cylinders of internal combustion engines, said cylinder head having a sealing surface arranged for engagement with a corresponding surface of a cylinder and provided with a circular compression ledge so dimensioned that said compression ledge will be completely flattened within the range of said connecting bolts in response to said connecting bolts being tightened to such an extent that the screw tension equals approximately from 1.5 to 3 times the ignition pressure multiplied by the inner diameter of said cylinder and divided by the number of connecting bolts.

2. A cylinder head according to claim 1, in which the compression ledge is so arranged on the sealing surface of said cylinder head that within the range of said connecting bolts a portion of the said sealing surface remains at both sides of said compression ledge following the flattening thereof.

3. A cylinder head of light metal for connection by connecting bolts with cast iron and steel cylinders of internal combustion engines, said cylinder head having a sealing surface arranged for engagement with a corresponding surface of a cylinder and provided with a plurality of circular compression ledges arranged in spaced relationship to each other and so dimensioned that said compression ledges will completely flatten within the range of said connecting bolts in response to said connecting bolts being tightened to such an extent that the screw tension equals approximately from 1.5 to 3 times the ignition pressure multiplied by the inner diameter of said cylinder and divided by the number of connecting bolts.

4. A cylinder head according to claim 1, in which the compression ledge has a height of approximately .2 millimeter.

5. A cylinder head of light metal for connection by connecting bolts with cast iron and steel cylinders of internal combustion engines, said cylinder head having a sealing surface arranged for engagement with a corresponding sealing surface of a cylinder and provided with a compression ledge for direct engagement with the sealing surface of said cylinder, said compression ledge being dimensioned to completely flatten within the range of said connecting bolts when the latter are fully tightened thereby causing the entire sealing surface of the cylinder head within the range of said connecting bolts to bear against the sealing surface of said cylinder.
